Term of patent 14 years

(Cl. D91—3)

FIG. 1

FIG. 2

FIG. 3

FIGURE 1 is a perspective view of an aerator for faucets showing my new design; and

FIGURE 2 is a side elevation of the aerator shown in FIGURE 1; and

FIGURE 3 is a top plan view of the aerator shown in FIGURE 1.

The characteristic feature of my design resides in the specific shape of the faucet in combination with the curved upper rim of the aerator as shown.

I claim:

The ornamental design for an aerator for faucets, as shown and described.
